PULP STOCK FLOW CONTROL

John A. Rosmait, Appleton, Wis., assignor to D. J. Murray Manufacturing Co., Wausau, Wis., a corporation of Wisconsin

Application October 2, 1944, Serial No. 556,796

3 Claims. (Cl. 92—46)

1
This invention relates generally to improvements in the art of paper making, and relates more particularly to improvements in the construction and operation of mechanism for collecting, spreading and controlling the flow of effluent or pulp stock as it is discharged from the screens to the head boxes of paper manufacturing machines especially of the Fourdrinier type.

The primary object of my present invention is to provide an improved mode of collecting, distributing and controlling the flow of effluent stock as it passes from the screens to the head box of a Fourdrinier type of paper making machine or the like.

The consistency of effluent or pulp stock delivered from the screens toward the Fourdrinier wire of well known paper making machinery, is relatively low, that is, it has practically the fluidity of water and contains only from one-tenth to three-tenths of solid matter such as fibres, in suspension. Depending of course upon the so-called freeness or "slowness" of the stock, even at these low consistencies there is a definite tendency for the fibres to settle or flocculate into small bundles, thus producing lumpy and extremely undesirable formations. This condition is aggravated by aeration, turbulency, cross-flows, etc. as the fibre stock passes from the surge box and through the customary pipe headers, T's and elbows connecting the surge box with the first pass of the head box. The use of this prior type of conductors results in the production of numerous sharp turns, corners, and quiescent zones in which eddy currents and badly settled areas are constantly formed, thus causing slimy pulp formations to momentarily lodge and to subsequently break loose and to create lumps, holes, and spots in the final paper. This prior type of header piping also results in considerable loss in velocity head due to the sharp entrance of the stock and the subsequent multiple bends, and requires the screens to be located at elevations sufficiently high to compensate for these hydraulic losses and to properly deliver the effluent stock into the first pass of the head box against the relatively high static head existing therein, and this static head must constantly be maintained sufficient to accommodate the highest speeds at which the machinery is operable.

In these prior paper making systems, the last connection of the piping header usually terminates in three or more outlets, depending upon the width of the Fourdrinier wire; and these outlets are slots or holes cut into the rear wall of the head box and are adapted to discharge the

2
fluent stock at laterally spaced intervals into the lower portion of the first pass of the head box, which pass is ordinarily a relatively deep rectangular space having an upper outlet communicating with the second pass. The violent injection of the fibre bearing stock through these several outlets and the drastic change in direction of flow produced thereby, further reduces the velocity of flow within the head box and interferes with uniformity in paper production. Then too, at the higher speeds of these paper making machines, the level of the liquid in the head box between the first and last passes, is not nearly as high as during low speed operation, but at high speeds the level in the head box as a whole should be at a maximum. The relative elevation of the screens with respect to the Fourdrinier wire, is therefore dependent upon the maximum speed of the machine, and the elevation of the screen outlets must be sufficient to insure proper capacity of flow through the piping headers and head box and to constantly overcome all hydraulic losses. If, therefore, hydraulic losses are encountered due to the use of inefficient conduits between the screen and head box, raising of the screens in an effort to obviate such losses, augments the undesirable condition whenever the apparatus is operating at low speeds at which the levels in the head box are far below the top, and only a fraction of the high speed levels is needed above the wire deck for the production of heavier weight paper. Under such operating conditions when utilizing lesser flow capacities and somewhat higher pulp consistency in the prior circuitous conduits together with high screen elevations, cascading results and makes it practically impossible to produce sheets of paper of proper texture and thickness.

It is therefore a more specific object of the present invention to provide an improved system of stock flow control from the screens to the wires of a Fourdrinier type of paper making machines, which eliminates all of the above mentioned difficulties, and which enables efficient production of paper of desired thickness and substantial uniformity and any desired practical speeds.

Another specific object of this invention is to provide improved apparatus for controlling the flow of effluent stock from a surge box or the like to the first pass of the head box of a paper making machine, embodying a minimum number of turns or changes in direction of flow, and of such formation that hydraulic losses are minimized and excessively high screen elevations are made unnecessary.

A further specific object of the invention is to provide an improved conduit assemblage for conducting fibre pulp stock from the screens to the head box of a paper producing machine, wherein the velocity of flow of the liquid delivered from the surge tank is gradually decelerated and converted into pressure energy sufficient to effectively overcome the static pressure head in the first pass of the head box under all conditions of operation.

Still another specific object of my invention is to provide improved mechanism for effecting uniform delivery of the effluent pulp stock into the first pass of the head box of a paper making machine, throughout the entire width of the box and in parallel directions, and for regulating or controlling the flow into the head box so as to produce smooth entry and to avoid undesirable turbulency and agitation.

An additional specific object of this invention is to provide improved instrumentalities for conducting the stream of pulp stock through a paper making machine, in a manner which will avoid eddy currents while aiding in deaeration of the effluent stock and causing the liquid to flow in a solid and smooth stream throughout its course.

Another specific object of the invention is to provide a simple and compact flow distributing and control unit which may be used either singly or in multiple and applied to either existing or new paper making installations at moderate cost, so as to insure proper flow under varying conditions of operation, and which is also highly flexible in its adaptations and efficient in normal operation.

These and other specific objects and advantages of my invention will be apparent from the following detailed description.

A clear conception of the features constituting the present improvement, and of the construction and operation of several types of my improved flow control mechanism, may be had by referring to the drawings accompanying and forming a part of this specification wherein like reference characters designate the same or similar parts in the various views.

Fig. 1 is a diagram or flow sheet illustrating a typical Fourdrinier type of paper making installation showing the general location of my improved apparatus;

Fig. 2 is a somewhat enlarged part sectional side elevation of the improved flow control unit showing the same associated with the screen outlet, surge box and head box the latter being shown in section;

Fig. 3 is a rear view of the assemblage shown in Fig. 2, embodying a single improved flow control unit;

Fig. 4 is a further enlarged central vertical section through a type of the improved flow control unit having a flow decelerating tube which is of circular cross-section throughout its length;

Fig. 5 is a top view of a single flow control unit such as shown in Fig. 4;

Fig. 6 is a still further enlarged vertical section through one of the flow regulating gates of my improved control assemblages;

Fig. 7 is a part sectional top view of another type of the improved flow decelerating tube, having circular cross-section at the top and elliptical cross-section at the enlarged bottom portion thereof; and

Fig. 8 is a somewhat diagrammatic top view of a multiple installation of my improved flow control unit.

While the invention has been shown and described herein as being especially adapted for use in connection with Fourdrinier paper making machines of variable capacity and characteristics, it is not my desire or intention to unnecessarily restrict the scope or utility of the improved features by virtue of this specific application thereof.

Referring especially to Fig. 1 of the drawings, the typical paper making installation shown diagrammatically therein, comprises in general, a battery of pulp screens 10 which are normally abundantly supplied with effluent or pulp stock 11 from a flow box 12 by a fan pump 13, and having screen outlets 14 of well known construction for delivering the effluent stock 11 into a surge box 15; an endless Fourdrinier wire 16 of any suitable width coating with breast and couch rolls 17, 18 respectively, and having a slice or inlet 19 which normally receives the pulp stock 11 from a multiple pass head box 20 of usual construction; and one or more flow decelerating tubes 21, flow spreaders 22, and flow control gates 23 of improved structure interposed between the surge box 15 and the lower rear inlet end of the head box 20.

The improved flow control assemblages embodying my present invention and which are adapted to be interposed between the surge box 15 and the head box 20, may be constructed as units of any desired capacity adapted to be utilized either singly or in multiple depending upon the width of the Fourdrinier wire 16, and the decelerating tubes used in these improved assemblages may also be of different types.

As specifically illustrated in Figs. 2 to 5 inclusive, the flow decelerating tube 21 of each unit, comprises a frusto-conical upright sheet metal tube having circular cross-section throughout its length but being of gradually enlarged diameter from its upper inlet to its lower outlet. Each frusto-conical tube is provided with a series of four internal radial vanes 24 the inner edges of which are parallel and terminate in a common circle concentric with the tube axis. The upper smaller inlet end of each decelerating tube 21 is in direct and open communication with the lower outlet 25 of the surge box 15, and the lower enlarged outlet end of the tapered tube 21 is provided with a cylindrical apron 26 which is in open communication with the adjacent spreader 22.

As particularly illustrated in Figs. 7 and 8, the slightly modified flow decelerating tube 21' of each unit, comprises an upright sheet-metal tube having gradually downwardly expanding cross-sectional area of circular cross-section at its smaller top or inlet end and of elliptical cross-section at its enlarged bottom or outlet end. This modified tube 21' is also provided with a series of four internal radial vanes the inner edges of which are parallel, and the smaller inlet end of the decelerating tube 21' is adapted to communicate directly with a surge box outlet 25 while the lower elliptical outlet end is provided with an apron 26' having uniform elliptical transverse cross-section with the major axis of the ellipse lying in a plane extending across the end of the head box 20 and transversely of the direction of flow through this box.

The improved flow spreaders 22 are adapted to cooperate with either type of decelerating tube 21, 21', and each of these spreaders 22 comprises a sheet metal casing which is laterally widened or spread out to the full width of a small standard head box 20 as in Figs. 3 and 5, or to one-half the width of a larger head box 20 as in Fig. 8, or to

one-third of a still larger box in installations of still greater capacity. The width of the spreaders 22 may be standard in the individual flow control units, and each spreader casing has an inclined bottom 27 directly beneath the apron 26, 26' of the adjacent central decelerating tube 21, 21', and also has a front lower outlet slot 28 communicating with the extreme lower rear end of the first pass 29 of the adjacent head box 20. Diagonal partitions 30 which radiate from the central axis of the corresponding decelerating tube and which divide the slot 28 into three parts of equal length, are also provided within each spreader 22, and these partitions may be either plane as in Fig. 5 or curved slightly away from the central plane of the spreader as in Fig. 8.

As indicated in Figs. 2, 4, 5 and 6, my improved flow regulating gates 23, are flexible elongated elements swingably suspended from spreader nozzles 31 which are in open communication with the spreader slots 28. As shown, there are three independent gates 23 associated with each spreader 22, and each gate is secured to the adjacent nozzle 31 by means of a curved plate 32 and cap screws 33, and is adapted to be swung from one dot-and-dash line position to another as illustrated in Fig. 6, by means of an independently adjustable actuating rod 34, all of which extend upwardly through the first pass 29 of the head box 20. The lower end of each adjusting rod 34 extends through a slot 35 formed in a tubular bead 36 formed at the outer swinging end of the adjacent gate 23, and is provided with an integral transverse bar 37 snugly engaging the corresponding bead 36. The upper end of each adjusting rod 34 is screw threaded and coacts with a hand wheel 38 having a hub 39 journaled for rotation in a bracket 40, and each rod 34 is also provided with upper and lower stop collars 41, 42 for limiting the opening and closing of the gates 23, see Fig. 4. The swinging gates 23 cooperate with the bottom of the head box 20 to provide smooth transition slots leading into the first pass 29, and these gates may be independently adjusted so as to provide for different delivery openings at different portions of the slots 28 and nozzles 31.

As previously indicated, the improved flow decelerating spreader and regulating units may be utilized either singly as in Figs. 3 and 5, or in multiple as in Fig. 8, and their use in multiple is not necessarily limited to two units. These units may also be applied either to new installations or to existing installations having Fourdrinier wires 16 of standard widths, thus facilitating manufacture of the units in large lots and application thereof to the paper making machines. Since the normal functioning of the circular and elliptical sectioned tubes 21, 21' is substantially the same, it will suffice to describe the normal operation of only one of these alternative structures.

During normal operation of the improved flow control units, the screens 10 will be receiving an abundant supply of pulp stock 11 from the flow box 12 past the fan pump 13, and after treating the effluent stock, the screens deposit the material into the surge box 15. From the surge box 15, the fibrous pulp 11 flows through the outlet opening 25, into the decelerating tube 21 wherein the velocity of flow is gradually decelerated due to the gradually increasing cross-sectional area, while excessive swirling or whirling of the stream is prevented by the radial vanes 24. Following this initial deceleration of the advancing pulp, the direction of flow is gradually changed from vertical to approximately hori-

zontal, by the inclined bottom 27 of the spreader 22 and the stream is further decelerated, spread and widened out to the full width of the outlet slot 28, by the rear, top and bottom walls of the spreader casing. The partitions 30 within the spreader 22 also function to prevent eddies in the advancing spreading stream and to divide the same into segregated adjoining parts flowing through the slot 28 in substantially parallel directions. As the effluent stock flows through the nozzles 31 and past the gates 23 it enters the lower portion of the first pass of the head box 20 at relatively high velocity but without turbulence or excessive agitation, and under pressure sufficient to overcome the static head of the liquid within the pass 29. The individual gates 23 may be readily adjusted with the aid of their manipulating rods 34 and hand wheels 38 so as to insure smooth entry of the liquid stock into the head box 20 throughout the entire width thereof, and the entering effluent stock subsequently flows through the successive passes of the head box and is eventually deposited upon the Fourdrinier wire 16 through the inlet 19. In this manner the improved flow control mechanism gradually conducts the fibre stock from the surge box 15 to the head box 20 with but a single gradual change in direction of flow, while simultaneously converting the velocity of flow into pressure energy sufficient to overcome the static head and also avoiding turbulence and eddies.

From the foregoing detailed description of the construction and operation of my improved pulp stock flow control system, it should be apparent that the invention provides control mechanism which besides being simple and compact in construction, is also highly efficient in operation and functions automatically after the gates 23 have been set to meet desired operating conditions. The improvement may obviously be embodied in units of predetermined capacity adapted to be used either singly or in multiple, and each unit is capable of effectively collecting, decelerating, distributing and controlling the flow of liquid therethrough, and is devoid of multiple bends, corners, and quiescent zones in which fibres are apt to flocculate or gather. While the circular decelerating tube 21 and apron 26 may perhaps be more readily constructed and applied to the spreader 22, the elliptical or oval type of tube 21' and apron 26' facilitates lateral spreading and distribution of the effluent stock, and both types of tubes as well as the spreaders 22 may be readily constructed of sheet metal and at exceedingly moderate cost. The use of the baffles 24 in the decelerating tubes and of the partitions 30 in the spreaders 22, eliminates swirling and turbulence and aids in proper distribution of the stock, and the independently manipulable gates 23 enable the operator to readily and effectively control the flow so as to insure uniform distribution throughout the entire width of the head box 20. It is also noteworthy that with my improved assemblage, the single change in direction of flow of each stream, is accomplished at the point of maximum cross-sectional area and minimum velocity thereof and just prior to final distribution and injection of the liquid into the head box, thus permitting most efficient and smooth spreading of the effluent stock without creating undesirable disturbances. The depending aprons at the lower ends of the expanding decelerating tubes, also enhance the final spreading and distribution, and the gates 23 may be readily formed of flexible sheet material and are

7
movable within predetermined fixed limits to provide efficient extensions of the final nozzles 34 for insuring streamlined and smooth injection of the fluent stock under pressure, into the head box 28. The improved construction and formation of the gates 23 and their actuating mechanisms, also insures maximum life thereof and enables the operator to conveniently adjust the several independent gates from a remote and accessible station.

It should be understood that it is not desired to limit this invention to the exact details of construction or to the precise mode of operation, herein shown and described, for various modifications within the scope of the appended claims may occur to persons skilled in the art.

I claim:

1. In combination with the surge and head boxes of a paper making machine, means for initially decelerating the flow of effluent stock discharged from the surge box and for converting its velocity energy into pressure, means for spreading the stock while under considerable pressure and as it flows away from said decelerating means, means for directly delivering the spread stock under pressure into the lower portion of the first pass of the head box throughout the entire width of the latter, and means for locally varying the cross-sectional area of said delivery means to insure uniform distribution of the stock.

2. In combination with the surge and head boxes of a paper making machine, means for initially decelerating the flow of effluent stock discharged from the surge box and for converting velocity energy thereof into pressure, means for preventing swirling of the stock as it passes through said decelerating means, means for laterally spreading the stream of stock flowing out of said decelerating means and for further converting velocity energy thereof into pressure, and means for directly delivering the spread stock under considerable pressure into the lower portion of the first pass of the head box.

3. In combination with the surge and head boxes of a paper making machine, means for initially decelerating the flow of effluent stock discharged from the surge box and for converting velocity energy thereof into pressure, means for preventing swirling of the stock as it passes through said decelerating means, means for laterally spreading the stream of stock flowing out of said decelerating means and for further converting velocity energy thereof into pressure, means within said spreading means for segregating the stock into a plurality of parallel streams, and means for directly delivering the spread stock under considerable pressure into the lower portion of the first pass of the head box.

4. A decelerating and flow control unit insertible between the surge and head boxes of a paper making machine, said unit comprising, a downwardly spreading tapered tube for initially decelerating the flow of effluent stock discharged into the tube from the surge box and for converting velocity energy thereof into pressure, vanes in said tube for preventing whirling of the liquid flowing therethrough, a spreader in open communication with the outlet end of said tube for changing the direction of flow of the initially decelerated stream and for spreading it laterally to further convert velocity energy thereof into

pressure, and nozzles for delivering the spread stream under pressure created by said tube and spreader into the lower end of the first pass of the head box.

5. A decelerating and flow control unit insertible between the surge and head boxes of a paper making machine, said unit comprising, a downwardly enlarging tapered tube for initially decelerating the flow of effluent stock discharged into the tube from the surge box and for converting velocity energy thereof into pressure, a spreader in open communication directly with the outlet end of said tube for changing the direction of flow of the initially decelerated stream and for spreading it laterally, partitions within said spreader for dividing the stream into segregated parallel flow sections, and nozzles for delivering the spread stream under pressure created by said tube into the lower end of the first pass of the head box.

6. A decelerating and flow control unit insertible between the surge and head boxes of a paper making machine, said unit comprising, a downwardly enlarging tapered tube for initially decelerating the flow of effluent stock discharged into the tube from the surge box and for converting velocity energy thereof into pressure, a spreader in open communication directly with the outlet end of said tube for changing the direction of flow of the initially decelerated stream and for spreading it laterally, nozzles for delivering the spread stream under pressure created by said tube into the lower end of the first pass of the head box, and independently adjustable gates for controlling the flow through said nozzles.

7. A decelerating and flow control assemblage for paper making machines having surge and head boxes, said assemblage comprising, a downwardly expanding upright tube having its smaller upper inlet end directly communicable with the surge box, said tube having circular transverse cross-section at its upper inlet end and oval transverse cross-section at its lower outlet end, a spreader in open communication with the larger lower outlet end of said tube and having a bottom disposed in vertical alignment with the tube for changing the flow from vertical to approximately horizontal, and independently adjustable means for regulating the delivery of effluent stock from said spreader into the lower portion of the head box at various localities throughout its width.

8. A decelerating and flow control assemblage for paper making machines having surge and head boxes, said assemblage comprising, a downwardly expanding upright tube having its smaller upper inlet end directly communicable with the surge box, a spreader in open communication with the larger lower outlet end of said tube and having a bottom disposed in vertical alignment with the tube for changing the flow from vertical to approximately horizontal, means within said spreader for dividing the flow therein into segregated parallel streams flowing toward the head box, and independently adjustable means for controllably admitting said streams under pressure to the head box through the several divisions and throughout substantially the entire width of the box.

JOHN A. ROSMAIT.
